UNITED STATES PATENT OFFICE.

HUGH W. SANFORD, OF KNOXVILLE, TENNESSEE.

MINE-CAR COUPLING.

Application filed April 25, 1924. Serial No. 708,877.

My improvement relates particularly to coupling mechanism designed for the automatic coupling of mine cars used on rail tracks which are unevenly supported and which have frequent and irregular curves and frequent changes in grade.

One object of the invention is to provide a simple coupling structure which will become engaged automatically when cars are pushed endwise against each other under the varying conditions mentioned above and which coupling structure will remain in engagement during pushing and pulling and jolting of the cars at varying velocity on such irregular trackage as I have above indicated.

A further object of the improvement is to provide such a coupling structure in a form which will permit disengagement of the coupling structures of adjoining cars and putting said structures into such position as to permit the rotating of one of the cars parallel to the length of the car without interference of the coupling or bumper elements of one car with the coupling or bumper elements of the adjoining car or cars, this arrangement allowing a train of such cars to be moved progressively through a rotary tipple, the car or cars at the time in the tipple being turned by the tipple for dumping, until all the cars have been thus emptied, and the cars being adapted to automatic recoupling by pushing or bumping the cars against each other.

A further object of the invention is to provide a bumper structure comprising bumper castings which are combined with the car bottom structure in an effective manner.

In the accompanying drawings,

Fig. 1 is a plan showing ends of cars provided with my improved coupling and bumper structure, the cars being in alignment with each other;

Fig. 2 is a side elevation of the structure shown by Fig. 1;

Fig. 3 is a plan similar to Fig. 1, the cars being out of alignment;

Fig. 4 is an upright, longitudinal section on the line, 4-4, of Fig. 1;

Fig. 5 is an upright section on the line, 5-5, of Fig. 1, looking toward the right;

Fig. 6 is an upright section on the line, 6-6, of Fig. 1, looking toward the right;

Fig. 7 is a perspective of the bumper casting in the right hand part of Fig. 1;

Fig. 8 is an upright section on the line, 8-8, of Fig. 1, looking toward the right;

Fig. 9 is a perspective of the bumper casting in the left hand part of Fig. 1;

Fig. 10 is an upright section on the line, 10-10, of Fig. 1, looking in the direction of the arrow;

Fig. 11 is an upright section on the line, 11-11, of Fig. 1, looking in the direction of the arrow;

Fig. 12 is a horizontal section on the line, 12-12, of Figs. 2 and 4.

Referring to said drawings, A is the wooden car bottom. This may be two and one-half inches thick. A¹ is a bumper block applied to the lower face of the car bottom and formed of wooden plank of suitable thickness, for example two and one-half inches. At each end of the car, the bumper block projects beyond the car bottom toward the adjacent end of the adjacent car to form an abutment for the bumper casting. The bumper block is secured to the car bottom by means of upright bolts which also extend through other parts, as will be described further on.

The car bottom, A, extends across the width of the car and each end extends to a plane which is upright and perpendicular to the length of the car. At the end of the car shown by the right hand part of Figs. 1, 2, 3 and 4, the free end of the bumper block, A¹, conforms to and bears against the inner face of the lower flange, B¹, of the right hand bumper casting, B. Above the flange, B¹, said bumper casting has a flange, B². At the right of the flanges, B¹ and B², the casting B, has a horizontal floor, B³, which rests on the upper face of the wooden bumper block, A¹. At the right of said floor is an incline, B⁴, which rises to bring its upper face to the level of the upper face of the car bottom, A, at a short distance toward the left of the adjacent end edge of the car bottom. Thence said casting has a horizontal section which extends to the upper edge of the adjacent end of the car bottom. From said edge, a flange, B⁵, extends downward along the end of the car bottom and to the upper face of the bumper block. At each end of the section, B⁵, a tongue, B⁶, extends toward the right and is counter-sunk into the upper face of the car bottom. Midway between said wings, a tongue, B⁷, extends rearward from the section, B⁵, and is counter-sunk

105
110

into the upper face of the car bottom. The tongue, B^8 , is longer than the tongues, B^7 ; long enough to receive two bolts, as explained further on.

5 The draw bar, C , extends lengthwise across the car bottom, preferably from one end of the car to the other, and in the form shown by the drawings, rests on the upper face of the car bottom and on the tongue, B^8 , and the section, B^5 , and on the incline, B^4 , the end of the draw bar being inclined to conform to the incline, B^4 . An inclined bolt, C^1 , extends through the end of the draw bar and the incline, B^4 , of the bumper casting and serves to bind the draw bar to said casting. In the plane of the line, 6—6, of Fig. 1, which plane is upright and perpendicular to the length of the car, a bolt, C^2 , extends downward through the draw bar and the tongue, B^8 , and the car bottom, A , and the bumper block, A^1 , and the binder iron, C^4 , which is applied transversely against the lower face of the car bottom and the bumper block and extends upward at each side edge of the car bottom. Said bolt also extends through the middle tie plate, C^5 , which extends parallel to the length of the car and over-laps the binder iron, C^4 , and extends along the lower face of the bumper block nearly to the bumper casting flange, B^1 , where it is secured to the lower face of the bumper block by an upright bolt, C^7 , extending downward through the bumper casting floor, B^3 , and the bumper block and the tie plate.

At the right of the bolt, C^2 , a bolt, C^6 , extends through the draw bar, the tongue, B^8 , and the car bottom and the bumper block. In the plane of the line, 6—6, an upright bolt, C^8 , extends downward through each adjacent tongue, B^7 , and the car bottom and the bumper block and the binder iron, C^4 .

On the line, 5—5, four more bolts, C^7 , extend through the bumper casting floor and the bumper block.

At each side edge of the bumper casting an upright flange, B^9 , rises from the floor, B^3 , and is integral with the upper flange, B^2 , and extends from said flange to the flange, B^6 , and is integral therewith.

The two flanges, B^1 and B^2 , of the bumper casting, B , together form a bumper casting wall which has its outer face curved in an upright plane and also in a horizontal plane.

Turning now to the left hand part of Figs. 1, 2, 3 and 4, A is again a part of a wooden car bottom and A^1 is the bumper block. It is to be understood that there may be a separate bumper block at each end of the car or a single piece may extend from end to end of the car and each end of said piece serve to co-operate with the car bottom for securing and staying the bumper castings.

D is the bumper casting placed on the end of the car opposite the end which bears the bumper casting, A . This casting has a top plate, D^1 , and a cross wall, D^2 , extending downward from the top plate. Extending to the right from the cross wall and downward from the top plate are outer or side walls, D^3 . To the right of the cross wall, the middle part of the top plate, D^1 , is omitted. From each edge thus formed from the top, an inner upright wall, D^4 , extends downward. At each side of this casting, a flange, D^6 , extends horizontally away from the adjacent side wall, D^3 , and rightward from the cross wall, D^2 , said flanges being integral with said walls, D^2 and D^3 . At the right, this casting has the outer upright wall, D^5 , which extends downward from the right hand edges of the top plate, D^1 , and from each side wall, D^3 , to the adjacent inner upright wall, D^4 , and from each wall, D^4 , to the other wall, D^4 ; but this part of the wall, D^5 , does not extend upward as high as the top plate, this part of the wall, D^5 , being left low to make room for the hook, as will be hereafter described. The wall, D^5 , stands below the level of the lower edges of the walls, D^3 , D^4 and the flanges, D^6 . This outer cross wall forms the bumper face of the casting.

In the left hand part of each inner wall, D^4 , is a bearing, B^7 , which opens downward and receives the journal, E^3 , of the hook, E . The hook, E , extends from its journal rightward between the walls, D^4 , and across the wall, D^5 . The journal, E^3 , is only long enough to reach across the walls, D^4 . The lower part of said journal rests on the bumper plate, A^1 . Thus the walls, D^4 , and the transverse wall, D^2 , and the bumper plate together form a bearing for the journal, E^3 .

On each end of the journal is a wrist, E^4 . These wrists are located at the left and a little above the axial line of the journal. On the inner face of the outer cross wall, D^5 , and near each inner wall, D^4 , is an ear, D^8 , into which there is secured one end of a contracting coiled spring, E^5 , the other end of said spring being coupled to the adjacent wrist, E^4 . On the outer end of the hook, E , is a head, E^1 , on which is a point, E^2 , which is to engage the bumper casting, B , of another car.

The end of the car bottom, A , extends beneath the left hand part of the top plate, D^1 , and abuts against the left hand face of the cross wall, D^2 , that part of the top plate being counter-sunk into the bottom, A . The draw bar, C , extends across that part of the top plate. The bumper block, A^1 , lies beneath and bears against the bottom, A , and the cross wall, D^2 , and the flanges, D^6 , and abuts against the inner face of the outer cross wall, D^5 . The forward part of the bumper block is slotted to make room for

the lower parts of the walls, D³ and D⁴, (Fig. 12), the forward parts of said walls extending downward. As shown in Fig. 4, the upper face of the bottom block bears 5 against the journal, E³, and forms a support for that journal. Thus said journal is confined in its position by the bumper block and the walls, D⁴, said walls directly engaging said journals, and the body of the hook 10 being confined by the walls, D⁴, against side-wise movement.

A bolt, F, extends downward through the draw bar, C, the top plate, the bottom, A, the bumper plate, A¹, and the transverse 15 binder iron, C⁴. Said binder iron being like the binder iron, C⁴, at the other end of the car. At the left of the bolt, F, two similar bolts, F¹, extend through the draw bar, the top plate, the car bottom, and the bumper 20 block. At each side of the bolt, F, a bolt, F², extends downward through the top plate, the car bottom, the bumper block, the binder iron, and one end of the tie plate, F⁴. In each angle formed by the side walls, D³, and 25 the outer cross wall, D⁵, a bolt, F³, extends through the top plate and the space above the bumper block and through the bumper block and through the adjacent tie plate, F⁴.

When the hook, E, is in the lower or working position, the contracting coiled spring, E⁵, exerts force on the hook tending to hold the hook against turning upward in response to jolting of the car. When the hook is moved into the upright position, the rear 30 part of the spring is carried across the axial line of the journal, E³, of the hook, whereby the action of the spring is changed so as to exert force on the hook tending to hold the hook in the upright position. This position 35 is desirable when a train or trip of cars are to be pushed without being coupled and to be successively moved outward on branches of the track; and this position of the hook is especially desirable when a trip of cars 40 are put through a rotary tipple, the cars being successively stopped in the tipple and turned sidewise for discharging their load by gravity. An inspection of the drawings will show that when the hook is in the upright position, it is out of the range of the bumper structure of the adjacent car, so that 45 either car is free to rotate while their bumpers bear against each other.

The hook, E, is suited to effect automatic 50 coupling. For that operation, the hook is to be placed into the lower or horizontal position, the body of the hook resting on the upper edge of the wall, D⁵, of the bumper casting, D. This brings the point of the hook 55 below the upper edge of the flange, B², of the adjacent bumper casting, and when the two ears are pushed together, the hook is forced upward by said flange until the point 60 of the hook crosses and drops behind said flange. As above indicated, if automatic 65

coupling is not desired, the hook is placed into the upright position and held there by the action of the contracting coiled spring, E⁵.

A mine car coupling resembling the coupling of this application is made the subject matter of my application, Serial Number 546,050, filed March 23, 1922, for Letters Patent of the United States. In the present application attention is especially invited to the form of the bumper castings and to the manner of supporting those castings by combining them with the car bottom and the bumper block.

I claim as my invention,

1. A mine car coupling structure comprising two metal bumpers, the first having an engaging face which extends horizontally and transversely to the length of the car and the second having a bearing which is horizontal and transverse to the length of the car, a hook having a transverse journal in said bearing, and a spring engaging said journal at its end and outside the axial line of the journal and exerting force on the hook tending to hold the hook against movement when the hook is in the horizontal position and tending to hold the hook against movement when the hook is in the upright position, substantially as described.

2. A mine car coupling structure comprising two metal bumpers, the first having an engaging face which extends horizontally and transversely to the length of the car and the second having a bearing which is horizontal and transverse to the length of the car, a hook having a transverse journal in said bearing, a wrist seated on one end of said journal and outside the axial line of the journal, and a spring engaging said wrist and exerting force on the hook tending to hold the hook against movement when the hook is in the horizontal position and tending to hold the hook against movement when the hook is in the upright position, substantially as described.

3. A mine car coupling structure comprising two metal bumpers, the first having an engaging face which extends horizontally and transversely to the length of the car and the second having a bearing which is horizontal and transverse to the length of the car, a hook having a transverse journal in said bearing, a wrist seated on one end of said journal and outside the axial line of the journal, and a contracting coiled spring extending across said end and engaging said wrist and exerting force on the hook tending to hold the hook against movement when the hook is in the horizontal position and tending to hold the hook against movement when the hook is in the upright position, substantially as described.

4. A mine car coupling structure comprising two metal bumpers, the first being

- formed for engagement by the hook on the other bumper and the second being recessed to form part of a bearing which is horizontal and transverse to the length of the car, 5 a bumper block extending under said bumper and forming a part of said bearing, and a hook having a transverse journal in said bearing, substantially as described.
5. A mine car coupling structure comprising two metal bumpers, the first having an engaging face which extends horizontally and transversely to the length of the car and the second being recessed to form part of a bearing which is horizontal and transverse to the length of the car, a bumper block extending under said bumper and forming a part of said bearing, and a hook having a transverse journal in said bearing, substantially as described.
- 10 6. A mine car coupling structure comprising two metal bumpers, the first being formed for engagement by the hook on the other bumper and the second having upright parallel walls recessed to form part of a bearing which is horizontal and transverse to the length of the car, a bumper block extending under said bumper and forming a part of said bearing, and a hook having a transverse journal in said bearing, substantially as described.
- 15 7. A mine car coupling structure comprising two metal bumpers, the first being formed for engagement by the hook on the other bumper and the second being recessed to form part of a bearing which is horizontal and transverse to the length of the car, a bumper block extending under said bumper and forming a part of said bearing, a hook having a transverse journal in said bearing, and a spring in engagement with the journal, substantially as described.
- 20 8. In a mine car coupling structure, a metal bumper having an outer transverse wall and being recessed to form part of a bearing which is horizontal and transverse to the length of the car, a bumper block extending under said bumper and abutting against said transverse wall and forming the lower part of said bearing, substantially as described.
- 25 9. In a mine car, the combination of a car bottom, a bumper block applied to the lower face of the car bottom and extending beyond the end of the car bottom, a metal bumper having a horizontal face resting on the car bottom and having upright walls abutting against the end edges of the car bottom and the bumper block, a tie plate under the bumper block, and bolts extending through the metal bumper and the bumper block and through the bumper and the car bottom and the bumper block and the tie plate, substantially as described.
- 30 10. In a mine car, the combination of a car bottom, a bumper block applied to the lower face of the car bottom and extending beyond the end of the car bottom, a metal bumper having a horizontal face resting on the car bottom and having upright walls abutting against the end edges of the car bottom and the bumper block, a binder iron extending transversely across the under face of the bumper block, and bolts extending through the bumper casting and the car bottom and the bumper block and the binder iron, substantially as described.
- 35 11. In a mine car, the combination of a car bottom, a bumper block applied to the lower face of the car bottom and extending beyond the end of the car bottom, a metal bumper having a horizontal face resting on the car bottom and having upright walls abutting against the end edges of the car bottom and the bumper block, a draw bar extending over the metal bumper and the car bottom, a binder iron extending transversely across the under face of the bumper block, and bolts extending through the draw bar and the bumper casting and the car bottom and the bumper block and the binder iron, substantially as described.
- 40 12. In a mine car, the combination of a car bottom, a bumper block applied to the lower face of the car bottom and extending beyond the end of the car bottom, a metal bumper having a horizontal face resting on the car bottom and having upright walls abutting against the end edges of the car bottom and the bumper block, a binder iron extending transversely across the under face of the bumper block, tie bars under the bumper block, and bolts extending through the bumper casting and the car bottom and the bumper block and the binder iron and the tie bars, substantially as described.
- 45 13. In a mine car, the combination of a car bottom, a bumper block applied to the lower face of the car bottom and extending beyond the end of the car bottom, a metal bumper having a horizontal face resting on the car bottom and having upright walls abutting against the end edges of the car bottom and the bumper block, a draw bar extending over the metal bumper and the car bottom, a binder iron extending transversely across the under face of the bumper block, tie bars under the bumper block, and bolts extending through the draw bar, bumper casting, car bottom, bumper block, binder iron and tie bars, substantially as described.
- 50 14. In a mine car, the combination of a car bottom, a metal bumper having a plate resting on the car bottom and having an upright wall abutting against the end of the car bottom, bolts securing the bumper to the bottom, a hook hinged on the bumper, and a spring engaging the bumper and the hook and tending to hold the hook in either of its two positions, substantially as described.

15. In a mine car, the combination of a car bottom, a bumper block applied to the lower face of the car bottom and extending beyond the end of the car bottom, a metal bumper having a horizontal face resting on the car bottom and having upright walls abutting against the end edges of the bottom and the bumper block, bolts securing said members to each other, a hook hinged 10 on the bumper, and a spring engaging the bumper and the hook and tending to hold the hook in either of its two positions, substantially as described.

16. A mine car coupling structure comprising two metal bumpers, the first being

formed for engagement by the hook on the other bumper and the second being recessed to form part of a bearing which is horizontal and transverse to the length of the car, a hook having a transverse journal in said bearing, a spring extending across one end of said journal and engaging said journal outside the axial line of said journal, substantially as described.

In testimony whereof I have signed my name, this 23rd day of April, in the year one thousand nine hundred and twenty-four.

HUGH W. SANFORD.
